UNITED STATES PATENT OFFICE.

JAMES F. MOYNIHAN, OF STONEHAM, MASSACHUSETTS.

APPARATUS FOR MANUFACTURING OIL OR WATER GAS.

SPECIFICATION forming part of Letters Patent No. 625,588, dated May 23, 1899.

Application filed January 5, 1899. Serial No. 701,180. (No model.)

To all whom it may concern:

Be it known that I, JAMES F. MOYNIHAN, a citizen of the United States, and a resident of Stoneham, in the county of Middlesex and 5 State of Massachusetts, have invented certain new and useful Improvements in Apparatus for Manufacturing Oil or Water Gas, of which the following is a specification.

My invention relates to apparatus for manufacturing oil or water gas; and it consists of a preferably circular retort consisting of an outer wall of fire-brick and an inner wall of iron, said retort being preferably provided with an observation-tube, around which is arranged a baffling or refractory material, and preferably series of plates nearly filling said retort, said baffling material herein shown as a checker-work of brick, a space being left at its upper end to form a mixing-chamber. 15 Around this retort is an outer casing of fire-brick, forming a fuel-chamber or generator having near its lower end a circular grate, the space between the outer casing and the retort being supplied with fuel to produce the heat required within the retort, into which oil, steam, 20 and air may be admitted as will be desired.

My invention further consists in certain details of construction, as hereinafter set forth, and pointed out in the claims.

30 Referring to the accompanying drawings, Figure 1 represents a vertical section of an apparatus for manufacturing gas embodying my invention. Fig. 2 is a horizontal section taken on line *x* *x* of Fig. 1. Fig. 3 is a similar view taken on line *y* *y* of Fig. 1.

A represents the circular outer wall of the fuel-chamber or generator. In the center of the inclosed space is arranged a retort *B*, formed of an outer wall of refractory materials, such as fire-brick, lined on the inside 40 with an iron shell *b*.

C is a circular grate arranged between the outer wall *A* and the retort *B*, and *D* is the ash-pit, from which extend exhaust-pipes *E* to create a draft to support combustion of the fuel. The retort *B* is closed at its upper end by an iron cap *a*, protected on the outside by fire-brick, and through which passes, as herein shown, an observation-tube *G*, that extends 45 down nearly to the bottom of the retort. The retort *B* is also provided with supporting-bars

55 *F*, carried in their central portion by a wall *F'*. Upon the top of the bars *F* and around the observation-tube *G* is arranged a series of rows of refractory brick *c*, set edgewise, with a space between each row, upon the top of which is arranged another series of rows of bricks set at right angles thereto, a space being left between each row, and upon which is another series of rows of bricks set at right 60 angles thereto, with a space between each row, and upon which is placed a plate *d*, that covers about three-quarters of the diameter of the retort and upon which brickwork, as before described, is placed, which is covered by 65 plates, the opening between the plates and side of the retort being opposite to that of the first plate. The retort is filled nearly to the top with refractory brick and plates, as described, the space between the straight edges 70 of the plates and the side of the retort alternating, so as to cause the gases to pass through the retort in a serpentine form. Above the top row of brick and the top of the retort is a space *H*, that is utilized as a mixing-chamber. 75

I are pipes by which hydrocarbon oil, superheated steam, and air may be injected into the retort *B*.

J is a metal plate forming a cap or cover for the apparatus and is provided with openings *j* *j* *j*, fitted with covers *k*, by which fuel can be supplied as required.

80 The observation-tube *G* is fitted at its upper end with a removable cap or plug *g*, so that when fuel is introduced into the generator dirt and dust will be prevented from passing into said tube, but when it is desired to ascertain the heat of the retort said cap or plug can be easily removed, when the observer, owing to the downdraft in the generator, can 85 look down the tube and by its color ascertain the heat, thereby enabling the operator to control the heat of the retort, so as to bring it to the best required for the production of gases that it is desired to create in said 90 retort, the degree of heat desired being obtained by manipulation of the drafts of the generator.

95 The top of the retort *B* may be provided with a number of ports *L*, that open into the outside fuel-chamber or generator *M*. These ports are fitted with covers *l*, whereby when 100

said covers are in place there will not be any connection between the retort B and the fuel-chamber M, but when they are removed water-gases produced in the fuel-chamber may pass 5 into the retort B.

N is the gas-main by which the gas from the retort passes off to a gas-receiver.

P is an air-pipe to supply air to the under side of the retort B to commingle with the gas 10 as it passes off by the main pipe N.

Q Q are drip-pipes to carry off any tar that may accumulate in the apparatus or gas-main, and T is a manhole by which access can be had to the under side of the retort B, if required. 15

R are doors to give access to the fuel-chamber or generator for cleaning or other purposes.

In the manufacture of oil-gas the covers of 20 the ports L at the top of the retort are to be put in place, so as to prevent connection between the retort B and the fuel-chamber or generator M. The covers k of the openings j are removed and fuel is fed into the chamber M to the desired height, and one or more of the covers are left open sufficient to allow the required amount of air to pass in and through the fuel to the exhaust-pipe E, that is connected to an exhauster. (Not shown.) 25 Thus a draft is created sufficient to support combustion, the waste gases being also carried off by said exhaust-pipe. The pipe S being closed by a suitable valve, (not shown in the drawings,) hydrocarbon oil and, if desired, superheated steam and air may be introduced into the retort B through pipes I, and the heat of the fuel in chamber M will cause same to be converted into gas, which passes down through the spaces between the 35 brickwork and plates in said retort and passes off by the main pipe N.

In the manufacture of water-gas fuel is supplied to the generator M and brought to a proper heat, as before described. The covers 45 k are then adjusted to close the openings j, and the exhaust-pipe E is closed by a suitable valve. (Not shown in the drawings.) Superheated steam is then introduced into 50 and above the fuel in the generator through the pipes g f and when formed into gas may pass off by a pipe S.

If is desired to produce a combined oil and water gas, the pipe S is closed and the ports in the retort B are opened, so that the water-gas 55 will pass through said ports and commingle with the oil-gas as it passes through the retort B, and in this case carbureted gas may be manufactured.

If desired, the oil-gas and the water-gas 60 may be made separately and carried off to a suitable mixing-chamber outside of the generator, the water-gas passing off through the pipe S and the oil-gas through the pipe N.

It will be seen that by this apparatus oil-gas 65 and water-gas may be separately made and, if desired, mixed outside of the apparatus, or the apparatus can be used to manu-

facture carbureted water-gas, in which case the retort acts as a carbureting and fixing chamber.

I prefer to use the observation-tube; but I do not desire to limit my invention in this respect, as the apparatus is capable of use for manufacturing gases without necessarily employing the observation-tube.

What I claim is—

1. An apparatus for making gas for illuminating or heating purposes, a retort or gas-generator, an observation-tube passing down into same, said tube being surrounded by 80 brickwork and plates as described, in combination with an outer fuel-chamber, substantially as set forth.

2. An apparatus for making oil and water gas for illuminating or heating purposes, a retort surrounded by a fuel-chamber, an observation-tube in said retort, surrounded by brickwork and plates arranged as described, means for introducing oil, superheated steam and air into said retort, and a pipe at the 85 lower end of the retort for carrying off the gases produced, substantially as set forth.

3. An apparatus for making a combined oil and water gas for illuminating or heating purposes consisting of a retort surrounded by 95 a fuel-chamber, said retort having an observation-tube surrounded by brickwork and plates as described, and ports at its upper end forming a connection between the retort and fuel-chamber, means for introducing oil, super- 100 heated steam and air into the retort, and superheated steam into and above the fuel in the outer chamber, the water-gas passing into the retort through the ports, and commingling with the gases therein, substantially as set 105 forth.

4. An apparatus for making oil-gas and water-gas at the same time, said gases being distinct and free to be carried off independently of each other, said apparatus consisting 110 of a retort surrounded by a fuel-chamber, the retort having an observation-tube whereby the heat of the retort can be ascertained, means for introducing oil, superheated steam and air into said retort, means for causing 115 the oil-gas produced to pass off from the bottom of the retort, and means for introducing superheated steam into and above the fuel to produce water-gas that is carried off at the top of the fuel-chamber, substantially as set 120 forth.

5. In an apparatus for making gas for illuminating or heating purposes, a retort surrounded by a fuel-chamber, ports at the upper 125 end of the retort, doors or covers for said ports whereby gas may be made in both chambers and caused to commingle in the retort, or be carried off independently, as set forth.

6. An apparatus for making gas for illuminating or heating purposes consisting of a retort surrounded by a fuel-chamber, ports at the upper end of the retort forming a connection between said retort and fuel-chamber, covers for said ports, means for introducing 130

oil, superheated steam and air into the retort, and superheated steam into and above the fuel in the outer chamber, means for causing a downward draft through the fuel, and means for carrying off the gases, substantially as set forth.

7. In an apparatus for manufacturing gas, a gas-generator provided with grate-surface to support the fuel within said generator, a retort located within said generator, and surrounded by the fuel therein, an oil-inlet extending from outside of the generator into said retort, baffling or refractory material within said retort, and a gas-outlet for the retort, extending to the outside of the generator, substantially as set forth.

8. In an apparatus for manufacturing gas, an upright gas-generator provided with an air-inlet and a gas-outlet, and having a grate-surface upon which the fuel is supported, an upright retort located within said generator and extended above and below said grate-surface, an inlet for said retort, and a gas-outlet for said retort extended to the outside of the generator, as set forth.

right retort located within said generator and surrounded by the fuel therein, an inlet for said retort, and a gas-outlet for the retort extended to the outside of the generator, substantially as set forth.

9. In an apparatus for manufacturing gas, an upright gas-generator provided with an air-inlet and a gas-outlet and having a grate-surface upon which the fuel is supported, an upright retort located within said generator and extended above and below said grate-surface, an inlet for said retort, and a gas-outlet for said retort extended to the outside of the generator, as set forth.

In testimony whereof I have affixed my signature in presence of two witnesses.

JAMES F. MOYNIHAN.
